A. A. HORTON.
ADDING MACHINE.
APPLICATION FILED AUG. 1, 1916.

Patented July 8, 1919.

2 SHEETS—SHEET 2.

UNITED STATES PATENT OFFICE.

ALLEN A. HORTON, OF HIGHLAND PARK, MICHIGAN, ASSIGNOR TO BURROUGHS
ADDING MACHINE COMPANY, OF DETROIT, MICHIGAN, A CORPORATION OF
MICHIGAN.

ADDING-MACHINE.

1,308,787.

Specification of Letters Patent.

Patented July 8, 1919.

Application filed August 1, 1916. Serial No. 112,510.

To all whom it may concern:

Be it known that I, ALLEN A. HORTON, a citizen of the United States, residing at Highland Park, in the county of Wayne and State of Michigan, have invented certain new and useful Improvements in Adding-Machines, of which the following is a specification.

The present invention relates to improvements in so-called "indexing" means for determining the movements of actuating elements of adding machines of that type in which such elements are directly driven by keys, and means for preventing simultaneous depression of keys of the same denominational series. I have shown my present invention in two different forms as applied to such a machine as that illustrated in my prior Patent 1,156,600, issued October 12, 1915, though it is of course to be understood that the invention is not necessarily limited to its use in connection with that particular construction of machine. In that machine, as in others of the same general type, the operating keys are arranged in several denominational rows running from front to rear, and the several keys of any one row operate upon an actuating element sometimes termed a "column-actuator" which ordinarily is in the form of a lever upon which the keys act at different distances from its pivot, thereby imparting different degrees of movement to such lever. In carrying out my present invention in both forms here shown I arrange a series of stop devices for each row of keys, such stop devices being in the form of swinging plates arranged in tandem and collectively displaceable upon depression of any key, the limited range of displacement being such as to prohibit simultaneous depression of two keys. This of itself is a well-known expedient in the art but I cause such stop devices to additionally function as means for accomplishing the so-called indexing, or, in other words, definitely measuring the movement of the actuator to correspond with the key action. I believe such a combination to be novel and I also believe that my indexing arrangement is possessed of novelty aside from its combination with means for preventing simultaneous depression of keys.

In the drawings which accompany and form part of this specification Figure 1 rep-

resents a sectional left-side elevation of a machine embodying my invention in one of the two forms above referred to, all parts being shown at normal; Fig. 2 is a similar though somewhat condensed and abbreviated view in which the effect of depressing a key is illustrated; Fig. 3 is a vertical cross-section on the line 3—3 of Fig. 1; Fig. 4 is a perspective view of one of the stop devices; Fig. 5 is a perspective view of the front portion of a stepped stop-arm; Fig. 6 is a view similar to Fig. 1 illustrating the other form of embodiment of my invention above alluded to; Fig. 7 is a similar view of the front half of the machine showing a key depressed; Fig. 8 is a vertical cross-section on the line 8—8 of Fig. 6; and Fig. 9 is a perspective view of one of the stop devices.

No detailed description of the machine proper is necessary, in view of the disclosure afforded by my aforesaid patent, and I have here applied to corresponding parts the same reference characters. Thus the reference letter A designates the actuating lever or "column-actuator," B the triangular lever which carries its fulcrum, D a link connecting said triangular lever with gear segment E which drives the registering mechanism at the front of the machine. A' designates a link which connects the forward end of the lever A with a leg of the link D. F designates the numbered keys which operate upon the lever A at different distances from its fulcrum or pivot. The keys are normally upheld by springs as usual and a relatively strong spring G upholds the lever A. All of the parts just enumerated will be found in both sets of figures of the accompanying drawings.

Referring now more particularly to the form of construction illustrated in Figs. 1 to 5, the reference numeral 2 designates a series of pendent shouldered plates arranged along a row of keys. These plates are hung upon suitable frame cross rods 3 and their end portions are adapted to abut against one another but sufficient displacement of the plates is permitted to allow of a key stem passing down between two of them or a key at the end of the row passing down by the end stop plate. The key stems are formed with somewhat elongated laterally projecting portions or lugs *f* for so coöoperating with the said pendent plates. The shoul-

dered formation of the plate is such that intermediate key stem lugs occupy spaces between successive pairs of plates and the lugs of the end keys (1 and 9) stand respectively 5 just in rear and just in front of vertical shoulders of the end plates. It will therefore be clear that depression of any key will slightly displace the stop plates or certain of them and will set up a locked relationship 10 between the plates and all the other keys which will prevent depression of any one of them while the key in action is out of normal.

In carrying out my invention in the form 15 shown in these particular figures of the drawings I make each stop plate in yoke form as best illustrated in Fig. 4 and I provide a leg 2^a thereof which will serve as a means for definitely limiting the initial 20 stroke of the lever A as caused by depression of the key associated with that particular stop plate. In this connection I employ a long arm or lever 4 which is pivoted at the rear upon a frame cross rod 5 and extends forward to a point just in rear of the gear segment E. It is held in the proper vertical plane by engagement of a notched lug 4^d with a portion of the adjacent partition plate H which has a shoulder h to limit upward movement of the lever. This arm or 30 lever has a series of steps or lugs 4^a which coöperate respectively with the legs 2^a of the swinging stop plates, and at its forward portion has a series of steps or shoulders 4^b 35 which serve to definitely limit or prevent overthrow of the lever A. A spring 6 applied to the rear end of the stop arm or lever 4 tends to elevate its forward arm but is normally restrained by reason of engagement between a stud 7 on the triangular lever B and a depending arm 4^c of the lever 4. The leg of the link or bar D to which the link A' is coupled is extended and formed with a laterally projecting lug d for 45 coöperation with the steps or shoulders 4^b.

In operation the depression of a key F results in singling out the leg 2^a of the stop plate immediately to the rear of that key so that said leg controls the movement of the 50 stop lever 4 by reason of contact between the underlying lug or step 4^a of said lever and the bottom edge of said leg, as illustrated in Fig. 2 where the "2" key is shown depressed. It will be understood of course 55 that when the lever A moves down under actuation of the key the said stop lever 4 is released so that the spring 6 lifts its front portion. The stopping of that lever 4 by contact of one of its steps 4^a with one of the 60 legs 2^a locates the proper vertical step or shoulder 4^b in line with the lug d of the link or bar D, so that such step or shoulder will definitely limit forward movement of 65 said link or bar and thereby correctly measure the movement of the gear segment E,

or prevent any overthrow thereof which might result in incorrect registration.

There are eight of the vertical steps or shoulders 4^b and eight of the steps or lugs 4^a on the lever 4, to correspond with the keys numbered from 1 to 8. The "9" key requires no stop shoulder or step on the lever 4 because that key effects the maximum movement and the parts moved can be stopped or limited by a fixed part of the framework. 75 In the present instance the movement of the lever A by said "9" key is limited by abutment of the stud e against the forward end of its guiding slot c', said stud constituting part of the pivotal connection between the 80 triangular lever B and the bar D.

In the construction illustrated by Figs. 6 to 9 I dispense with the element of the long stop arm or lever with the eight vertical steps or shoulders, and arrange to have the swinging stop plates directly block forward movement of the link or bar which connects the triangular lever with the registering gear segment. That portion 20 of the swinging plate which functions to prevent simultaneous depression of keys is identical with the corresponding portion of the plates already described. The plate is yoke-shaped after the manner of the plate previously described but the formation at the side opposite that where the portion 20 is located differs in order to adapt it for co-operating directly with the link or bar D'. The latter is of somewhat different form from the link D illustrated in Fig. 1. Thus 100 it is of somewhat irregular form or contour longitudinally and it is formed with seven stop lugs d² variously positioned along its upper edge and of differing dimensions, and a single stop lug d³ on its under edge at the 105 forward part. These stop lugs are designed to coöperate respectively with the right-hand portions of the yoke-shaped stop plates. These portions of said plates are of varying longitudinal contour as illustrated 110 in Fig. 6. Each, except the one on the foremost plate, extends forwardly, being designated by the numeral 21, and at its forward extremity is turned laterally so as to form a stop lug 22 to coöperate with the corresponding stop lug d². In the case of the foremost plate the arm designated 21^a extends rearwardly but has a similar terminal stop lug 22 to coöperate with the lug d³ on the underside of the bar D'. The arm 21 120 of the next foremost plate runs past this arm 21^a of the foremost plate as shown in Fig. 6, and the latter is slightly offset as shown at 21^b in order to accommodate the other arm. 125

The displacement of stop plates 20 by depression of any one of the keys (except the "9" key which requires no special stop devices for limiting movement of the lever A) results in singling out the stop plate imme- 130

diately in rear of the operated key so that the lug 22 of the arm of such plate will coact with the corresponding lug d^2 (or d^3 in the case of the "1" key) to definitely and positively limit the forward movement of the link D' . Thus in Fig. 7 the "2" key is shown depressed and the foremost lug d^2 is illustrated as in contact with the lug 22 of the arm 21 of the plate 20 immediately in rear of said key.

In the construction shown by Figs. 6 and 7 it will be noted that the bar or link D' does not connect directly with the gear segment E , but is coupled to an arm E' which 15 arm is connected to the gear segment by a relatively strong spring E^2 . It will of course be understood that the arm and segment are independently journaled upon the frame cross rod e , and the object is to prevent injury to the registering mechanism in case of 20 its becoming obstructed or locked. In any such event the spring E^2 would yield to the force applied in striking a key.

I claim:

25 1. The combination of a vibratory actuator, a series of keys acting thereon, and a set of stops relatively arranged to prevent depression of two keys at once and also serving to block movement of the actuator at the position to which it is brought by a key.

30 2. The combination of a vibratory actuator, a series of keys acting thereon, and a set of stops arranged in tandem with provision for so limited displacement as to prevent 35 depression of two keys at once, said stops severally serving to block movement of the actuator at the position to which it is brought by a key.

3. The combination of a vibratory actuator, a series of keys acting thereon, and a 40 set of swinging stops arranged in tandem one for each key and displaceable to a limited extent by the same, said stops severally

serving to block movement of the actuator at the position to which it is brought by a key. 45

4. The combination of a lever, keys acting thereon at different distances from its pivot, a link coupled to the lever for longitudinal movement thereby, and a set of stops relatively arranged to prevent depression of two 50 keys at once and also serving to block movement of the aforesaid link at the different positions it assumes under key action.

5. The combination of a lever, keys acting thereon at different distances from its pivot, 55 a link coupled to the lever for longitudinal movement thereby, and a set of swinging stops arranged in tandem one for each key and displaceable to a limited extent by the same, said stops adapted when displaced to 60 block the said link at the different positions it assumes under key action.

6. The combination of a lever, keys acting thereon at different distances from its pivot, a swinging stepped stop-arm normally 65 restrained by the lever, and a series of overthrow-preventing stops, one for each key, adapted to variously limit the movement of said stop-arm whereby to set one or another of its steps or shoulders in position for 70 blocking movement of the lever.

7. The combination of a lever, keys acting thereon at different distances from its pivot, a swinging stepped stop-arm normally restrained by the lever, a link coupled to the 75 lever for longitudinal movement thereby, and a series of overthrow-preventing stops, one for each key, adapted to variously limit movement of said stop-arm whereby to set one or another of its steps or shoulders in 80 position for blocking movement of the said link.

ALLEN A. HORTON.
